CAR DOOR OPENER AND CLOSER

Glenn W. Merritt, Bowerston, Ohio, assignor to
 The Nolan Company, Bowerston, Ohio, a corporation of Ohio

Application November 16, 1950, Serial No. 196,038

3 Claims. (Cl. 254—135)

1

This invention relates to an improved door-opening and closing device, the invention being concerned particularly with a device for opening and closing sliding doors of the type employed on railway boxcars.

Boxcar doors are mounted commonly for sliding movement between positions of doorway opening and closure. Often considerable difficulty is experienced in operating these doors, as strains and stresses in the door frames, guides, and in the boxcar itself often cause the doors to bind and stick, a condition which presents severe mechanical difficulties in obtaining the desired sliding movement on the part of said doors.

It is an object of the present invention to provide a device capable of being readily connected or associated with a car door so that the latter may be quickly and easily operated by one man and moved between opened and closed positions.

It is another object of the invention to provide a boxcar opening and closing device comprising a pulley block around which a pawl-controlled operating chain is passed, the block being formed with a hook adapted for attachment to a door to be opened or closed, and the chain, in turn, being anchored at one end to a stationary part of the boxcar with the opposite end thereof free for manual operation, whereby when the chain is tightened from its free end, powerful forces, in an effective and properly applied manner, are set up to actuate the door.

It is another object of the invention to provide the pulley block of a car door-opening and closing device with an improved safety hook adapted for attachment to an associated car door, the hook being turnable in relation to the pulley block through an arc of approximately 180 degrees and yet is locked positively against such turning movement when in place and before pulling forces are applied thereto.

Another object of the invention is to provide a car door opener and closer of this character in which the pulley block is formed with a chamber having mounted therein a chain-engaging pawl, the walls of the chamber serving to enclose and protect the pawl, whereby to eliminate any interference in the operation of the pawl through its engagement with the adjoining sides of plain or corrugated boxcar doors.

A further object of the present invention is to provide a car door opener and closer which is of relatively light and compact construction so that it may be easily carried, conveniently applied with expedition and facility, and which will open

2

a door from completely closed position so as to avoid all necessity for preliminary opening of the door before application of the opener thereto.

Still a further object is to provide an opener of the character stated by means of which relatively great power can be applied to a door for opening or closing the latter, and to accomplish this end even when the doors and their guides are in a poor mechanical state.

10 Further objects and advantages of the invention will appear from the following detailed description and the accompanying drawings, wherein:

Fig. 1 is a side elevational view of a door opener and closer embodying the present invention, the same being partly broken away and shown in cross section to disclose underlying structure;

Fig. 2 is a detail fragmentary side elevational view of the adjoining portions of the swiveled hook and pulley block extension of my improved door-opening and closing device, the hook being shown in position in which turning movement thereof about its swiveled connection with the block extension may be effected;

25 Fig. 3 is a vertical longitudinal sectional view taken on the line III—III of Fig. 1;

Fig. 4 is a vertical transverse sectional view on the line IV—IV of Fig. 1;

Fig. 5 is a detail fragmentary perspective view disclosing the construction of the swiveled end of the movable pulley block hook;

Fig. 6 is a similar view disclosing the forwardly located pulley block extension to which the movable hook is swiveled;

Fig. 7 is a fragmentary sectional view, partly in side elevation, of the pawl and sheave construction of my improved door-opening and closing device, with the pawl shown in its position providing for the application of pulling forces to the operating chain of the device;

Fig. 8 is a vertical transverse sectional view on the line VIII—VIII of Fig. 7;

Fig. 9 is a side elevational view disclosing the application of the device to the sliding door of a boxcar.

50 My improved door opening and closing device comprises a pulley block which includes a housing 10, having spaced side walls 11. Between these walls, there is formed a pulley chamber 12, in which is rotatably mounted a chain pulley or sheave 13, the latter being supported for rotation in connection with an axle pin 14 carried by the side walls 11 and passing transversely through the chamber 12. A link chain 15 has its intermediate portion trained around the grooved

circumference of the pulley or sheave 13. One end 16 of said chain may carry a hook, see Fig. 9, while the opposite end 17 of the chain may be held by the hands for manual pulling.

Also formed between the side walls 11 of the block housing 10 is a pawl chamber 21, the latter being in communication as at 22 with the pulley chamber 12. Positioned in the pawl chamber 21 for pivotal movement about an axis 23 is a pawl 24. On one side of the axis 23, the pawl is weighted as at 25, while the opposite end of the pawl engages with the links of the chain 15. The chain-engaging end of the pawl is disposed immediately adjacent to a transverse web 26, forming a part of the housing 10, the pawl serving automatically to hold the car-anchored end of the chain under tension when the ring 17 is released, or pull on the outer end of the chain relaxed.

To connect the pulley housing with a car door, the housing, in this instance, is formed at one end, on its under side, with an extension 27, the opposite end thereof being formed with a stationary hook 28. The extension 27 is provided with a bore 29 in which is mounted for rotation and limited longitudinal sliding movement the cylindrical shank 30 of a turntable hook 31, the latter being adapted for attachment to a fixed bail-type handle 32 provided on the side of a conventional slidably mounted boxcar door 33. The turning movement allowed the hook 31 provides for convenience in applying or removing the hook relative to the door bail 32 and, also, the quick and ready alignment of the pulley block, and the pulley carried thereby, with the chain 15 when the latter is tightened. One end of the shank 30 is provided with a retaining nut 30a.

To close the opening of the bail-receiving jaw 34 of the hook 31 when the device is in use, so that the hook 31 will not become accidentally disengaged from the door bail, the extension 27 includes a forwardly projecting foot 35 which terminates adjacent to the outer end 36 of the hook 31, so that insufficient space will exist in the jaw opening formed between the foot 35 and the outer end 36 of the hook to permit of the passage of the door bail or handle therebetween.

When in this position, and to prevent rotation of the hook 31 about the axis of its swiveled shank 30, the inner end of said hook is formed with a laterally directed semicircular flange 37, the latter being provided midway between its ends with a notch 38, which is adapted to receive the upper end of a locking finger 39 integrally formed with and projecting upwardly from the foot 35. The finger 39 is of such width that when the hook 31 is forced inwardly, after release of chain tension, the shank 30 slides in the bore 29 of the extension 27 in a direction toward the pulley block, and the flange 37 will be moved to a position to the rear of the finger in which it registers with a notch 40 formed in the foot 35. With the flange 37 disposed in the vertical plane of the notch 40, the hook 31 may turn relative to the pulley housing or vice versa through an arc of approximately 180 degrees. The extent of this arc is determined by the employment of arcuately spaced shoulders 41 which are integrally formed on opposite sides of a flange 41a provided integrally on the hook 31 contiguous to its inner end and immediately adjoining the flange 37 of said hook. With the flange 37 positioned in the notch 40 and the inner end of the hook in contact with the circular outer face 42 of the extension 27, the turning movement between the hook 31 and the

pulley block will be limited by the engagement of one or the other of the shoulders 41 with a side of the foot 35 adjacent to the notch 40.

The operation of the device may be conveniently accomplished by connecting one end of the link chain with a stationary part of an associated boxcar, and the turnable hook 31 with the bail handle 32 of the sliding door of such a car. When the other end of the chain is initially pulled by an operator, the pulley block slides on the shank 30 of the hook 31, so that the locking finger 39 of the housing foot 35 enters the notch 38 formed in the flange 37 on the inner end of the hook 31.

By so occupying the notch 38 of the flange 37, the locking finger 39 prevents rotation of the hook 31 about the axis of the shank 30, and thereby maintains the outer end 36 of said hook 31 in the same plane as the foot extension 35 and the housing itself. By pulling on the free end 17 of the chain 15, to tighten the same, the chain rides around the circumference of the pulley or sheave 13, shortening the effective overall length of the chain and imparting sliding movement to the car door, effecting movement thereof to an open position.

In this pulling operation, tension is maintained at all times in the length of the chain 15 located between the car-anchored end 16 thereof and the link or links engaged by the pawl 24, the operating or free end 17 of the chain being free except when manually pulled. The web 26 serves to allow the pawl, under the irregularities in the formation of the links of the chain 15, to limit rocking movement of the pawl in response to the action of the stresses thereon. Any tendency of the chain to lose its tautness between the block and the anchored end 16 thereof is resisted by the pawl when the device is applied to a car door and the chain actively tensioned. It will be observed that the side walls of the pawl chamber enclose the pawl or detent and prevent any interference with the operation of the pawl through engagement of the latter with the sides of the car door, particularly when such sides are composed of corrugated sheeting.

I claim:

1. A car door opening and closing device comprising: a pulley block including a housing formed at one end with a hook-carrying extension having a bore, an attaching hook for said block, a shank formed with and projecting longitudinally from the inner end of said hook, said shank being mounted for rotation and limited sliding movement in the bore formed in said housing extension; a flange integrally formed with the shank-carrying end of said hook, said flange being provided intermediately thereof with a notch, and a rigid finger projecting laterally from the forward end of said extension and engageable with the walls of the flange defining said notch to restrain said hook against turning movement when said hook and pulley block are subjected to oppositely directed pulling forces.

2. A car door opening and closing device as defined in claim 1 and wherein the shank of the swiveled hook is provided at its outer end with a head-forming member, the latter being engageable with said extension to limit outward sliding movement of said hook in response to pulling forces tending to separate said hook from said pulley block.

3. A pulling device comprising a pulley block having a housing; a pulley rotatably mounted in said housing, said block being formed at one

end thereof with an integral extension provided with a longitudinally extending bore; a swiveled hook for said block; a shank projecting rigidly from the inner end of said hook for slideable and rotatable movement in said bore; a first laterally projecting flange integrally formed with said hook contiguous to the shank-carrying end thereof; a finger projection provided on the outer end of said hook extension, said projection being disposed for engagement with the walls of a notch provided in said flange to restrain said hook against rotation relative to said block when forces are applied to the block and said hook tending to separate the same, said extension being formed with a recess disposed for registry with the flange of said hook to admit of rotation of the latter relative to the block when the hook and block are forced together through longitudinal sliding movement of said shank; a

second laterally projecting flange integrally formed with said hook in immediately adjoining relationship with said first flange; and spaced shoulders provided on the second flange of said hook engageable with said block extension for limiting turning movement of the hook about the longitudinal axis of said shank.
